INVENTOR

William Brown

BY

John H. Polachek
ATTORNEY

ATTORNEY

UNITED STATES PATENT OFFICE.

WILLIAM BROWN, OF NEW YORK, N. Y.

FLYING MACHINE.

Application filed October 6, 1923. Serial No. 666,888.

To all whom it may concern:

Be it known that I, WILLIAM BROWN, a citizen of the United States, residing at New York, in the county of New York and State 5 of New York, have invented certain new and useful Improvements in Flying Machines, of which the following is a specification.

This invention relates to flying machines, 10 having more particular reference to a flying machine of the helicopter class, in which a rotary element of the turbine type exerts a downward suction of air to cause the machine to rise, the invention having for a 15 general object the provision of a novel flying machine of this type.

For further comprehension of the invention, and of the objects and advantages thereof, reference will be had to the following 20 description and accompanying drawings, and to the appended claims in which the various novel features of the invention are more particularly set forth.

Fig. 1 of the drawings is a fragmentary 25 horizontal sectional view of my improved flying machine, this view being taken on the line 1—1 of Fig. 2.

Fig. 2 is a transverse vertical sectional view thereof, taken on the line 2—2 of Fig. 30 1, the rotary element being shown in a different position than in Fig. 1.

Fig. 3 is a detail horizontal sectional view of the automatic valve control element.

Fig. 4 is a fragmentary vertical sectional 35 view, taken approximately along the same line as Fig. 2, and showing the control elements for the annular explosion chambers.

Fig. 5 is a fragmentary vertical sectional view taken on the line 5—5 of Fig. 1.

Fig. 6 is a side view of the complete machine.

Fig. 7 is a plan view showing the control means for the propulsion and steering device.

Fig. 8 is a detail vertical sectional view of one of the valve control devices.

Fig. 9 is a plan view thereof.

As here embodied my improved flying machine comprises a large disk-like member 10 50 which is of hollow construction and horizontally disposed. Fixed at opposite ends to this member are the front and rear cabins 11 and 12, the former of which is the pilot's cabin while the other may be used for any 55 desired purpose. Extending between these cabins, above the disk member 10, are two

wall elements 13 which enclose a space 13' for the passengers. The machine is mounted on suitable wheels 14.

Extending vertically through the space 13' 60 is a well 16 through which air is drawn downward to sustain the machine by the downward suction. Located in this well is a double flap valve comprising two hinged leaves 17 pivoted as at 17' on a common axis 65 on a crossbar 18 in the well and connected by links 19 with a screw 20' threaded through a grooved pulley-nut 20 mounted for rotation, but held against vertical movement, on rigid post 21 extending concentric of the member 10. Connected to the pulley 20 is a cord 23 which leads around suitable guide pulleys such as 24 to another pulley 25 provided with a crank handle 25', this pulley 25 being located near the operator's seat 11' in the cabin 11. Looped over the pulley 20 is a second cord 23' which is looped also over a pulley-nut 20° through which is threaded a screw 20° connected to an arm 20b on a flap valve 20° in an exhaust conduit 80 20d leading rearwardly from the member 10.

Carried within the member 10 is a rotary element whose rotation induces the suction through the well 16. This element comprises four curved arms 26 extending outward from central members 26' which freely surround the post 21. Extending through these arms are conduits which have their outer ends in the form of nozzles through which gases under pressure are delivered at 85 an oblique angle on vanes 28 carried by the cylindrical vertical wall of the member 10. These gases are obtained by the explosion of an air and hydro-carbon mixture, a pair of annular explosion chambers 30 being 90 provided and fixed to the said arms 26, these explosion chambers being of circular cross section. Pipes 32 which form the conduits above referred to lead from the respective chambers through the arms 26 and have 95 their outer ends in close proximity to the vanes 28. Air under pressure and gasoline, are introduced into the explosion chambers 30 and the mixture is then ignited as usual by an electric spark, water in small 100 quantities being introduced into the explosion chambers after the explosion has taken place, the water increasing the efficiency of the gases by the generation of steam and also preventing overheating of the explosion chambers. The compressed air is delivered 105 to the explosion chambers through pipes 48

suitably branched as at 50 to each chamber.

The compressed air is supplied to the explosion chambers from a number of air compressors having a general spoke-like arrangement with respect to the chambers 30 and each comprising the tandem cylinders 40 separated by heads 41 and in which are pistons 42 connected by rods 43 with an eccentrically disposed wristpin element 44, formed on the post 21. The air is conducted to the cylinders through branched pipes 46 in which are suitable checkvalves 47, and is discharged therefrom through the pipes 48 to which lead branches 48' having checkvalves 49 therein. From each of these pipes 48 (see Fig. 4) branches 50 in which are checkvalves 51 lead to the respective explosion chambers 30 and the air is adapted to be admitted in alternation to the said chambers, the admission of air being controlled by a sleeve valve 52 in the pipe having an opening 53 in the side thereof adapted to alternately register with the branches 50. The sleeve valve is adapted to receive longitudinal reciprocatory motion from a rod 54 connected thereto at one end and having at its opposite end a pivoted section 54' provided with a head 55, adapted to be engaged in spiral grooves 56 formed in adjacent faces of a pair of fixed disks 57 located concentrically with the chambers 30, the grooves in the two disks being respectively right and left hand. Projecting rigidly upward from the rod section 54' is a finger 58 which is adapted to engage the annular shoulders 59 to throw the said section upward and downward to engage the head 55 with the respective spiral grooves 56, the grooves in the two disks may vary in depth from end to end so as to cause the heads 55 as they travel along the groove in one disk, to be gradually moved toward the other one to facilitate transfer of the head from one groove to the other. The rod section 54' may have sufficient frictional engagement with the main rod length to be held in the position to which it is adjusted. As the rotary element moves, the sleeve valves 52 will be caused to reciprocate. To start the machine a number of compressed air tanks 60 are employed from which suitable branched pipes 60' lead to the respective explosion chambers. These pipes 60' have valves 61 thereon whose handles 61' thereon are operated in a manner to be presently set forth. Pipes 60' may lead from the air compressors 40 to the tanks 60.

Upon the pipes 32 leading from the explosion chambers 30 are valves 62 whose operating handles 63 are adapted to be engaged and moved to position with the valves open by means of heads 64 on a rod 65 fixed to the sleeve 52, springs 66 tending to keep these valves closed. The exploding of the charges in the chambers 30 is done by approaching

the contact elements 67 carried by the rods 54 with other fixed contact elements 68 which are wired to spark plugs or ordinary construction in the respective chambers.

As will be understood a vacuum will be created behind each of the arms 26 as it rotates, and the air is drawn downward through the well 16 and passes out through openings 70 in the bottom wall of the member 10 adjacent the edge thereof. These openings 70 may be controlled through the medium of sliding plate-valves 71 which are connected to levers 72 fulcrumed between their ends to the said member 10 as at 73. These levers 72 may be swung to positions varying the extent of opening of the apertures 70 by means of cords 74 connected thereto. These cords 74 are led around suitable pulleys 75 on the periphery of the member 10 and are then passed inwardly to connect to opposite ends of a weighted element 76 slidable freely in a curved guide 77 fixed under the member 10. For longitudinal balance other ropes 74' may lead around suitable pulleys to a second weighted element (not shown) similar to the element and extending transversely thereto.

Other apertures 78 are formed in the top wall of the member 10 and are controlled by valve plates connected to the levers 72 to be operated by the latter. Light tension springs such as 78' are connected to the cords 74 to hold the levers in position with the apertures 78 closed and the apertures 70 open. If the machine tends to tilt toward one side the weight 76 will shift and the openings 70 on the high side of the machine will be partly closed and those on the low side opened to greater capacity, a reverse action taking place with respect to the openings 78. Automatic balancing is thereby effected.

To steer and propel my improved flying machine I provide a pair of rotary cylinders 82 which control the mouths of conduits 16' leading laterally from the wall 16 these cylinders having formed in the sides thereof the openings 83. In these cylinders are pistons 86 fixed on rods 87 on which the shutters are also mounted to swing, the shutters having an ordinary feather connection with the rods so as to permit the latter to move longitudinally independently of the shutters, while rotary movement of the rods swings the shutters. Control of these parts is effected by the steering element illustrated in detail in Fig. 7 and which is mounted in the cabin 11. This steering element comprises an outer hollow shaft 90 and an inner solid shaft 91 suitably supported in a frame element 92 and having handwheels 90' and 91' on their respective ends. Fixed to the hollow shaft 90 is a mutilated bevel gear 93 which is adapted to be brought selectively into engagement with either one of a pair

of bevel pinions 94 mounted on transverse shafts 95, these shafts having other bevel pinions such as 96 thereon which mesh with like pinions such as 97 having a non-rotative 5 but sliding engagement with the rods 87. Upon the solid shaft 91 are fixed the sprocket wheels 98 over which are looped the chains 99 engaging also over like sprocket wheels such as 100 having threaded bores through 10 which pass the threaded ends of the rods 87.

By adjusting the shutters 82 the area of the openings into the conduits 16' may be varied independently in each, while by adjusting the pistons 86 backward or forward 15 the direction of flow of the air inward through the conduits may be caused to be either backward or forward, causing the machine to be propelled in a forward or backward direction, steering of the machine 20 being effected by individually adjusting the shutters 82.

The gasoline is contained in a tank 110 located near the rear of the machine and flows by gravity through a suitable pipe, 25 through a passage 111 in the post 21 and into a semi-cylindrical chamber 112 partially surrounding the post 21 but fixed to the rotary element, the flow of gasoline only taking place at the time the ports in the post and 30 the chamber wall are in registry. The gasoline is fed from this chamber to tanks 113 supported by the rotary element by means of a pump 114 which is operated by a crank shaft 115 rotated by means of meshing gears 35 116 and 117 fixed respectively to the said shaft and the post 21. A similar arrangement, comprising a chamber 118 connected to a supply tank 119', and a pump 119 is provided to introduce small quantities of 40 water into the explosion chambers at the time of the explosion. The gasoline is delivered from the tanks to the explosion chambers through pipes 120 having valves 121 thereon which are controlled by means 45 operated by the sleeves 52 as shown in Fig. 4. These pipes 120 have other valves 122 thereon for hand control, these valves having handles 122'.

Formed on the cylindrical wall of the 50 member 10 is an inwardly projecting annular flange 125 and from the space below said flange pipes 126 lead to the centre of the machine and conduct the air which is shown by the arrows 26 into said space inward to enter the pipes 46. These pipes 126 lead upward at their inner ends into a horizontal partition member 127 in which are flap valves 128.

These valves 128, as well as the valves 61 60 and 122 are operated individually by the means shown in Figs. 8 and 9. A number of pairs of curved arms 135 have attached thereto ropes 136 which lead to the valve handles. Connected to these arms are 65 fingers 137 which are attached to opposite

reaches of ropes 138 leading around pulleys 139. These ropes connect, for the flap valves 128, to a foot lever 140, and for the other valves to hand levers such as 141 which may be set in position with the valves 70 either open or closed.

As will be apparent, the arrangement of control means for the air above set forth permits the full power of the engine to be utilized for lifting, or for propulsion. 75

This machine may be provided with a number of parachutes suitably located thereon, and which may be opened in the event of accident.

Having thus described my invention what 80 I claim as new and desire to protect by Letters Patent of the United States is as follows:

1. In a flying machine a hollow disk-like member, having air intake and outlet openings, vanes on the circumferential wall of said member, a rotary element therein having a pair of arms projecting close to said vanes, said arms being of a width substantially equal to the distance between the 90 radial walls of said member, and means carried by said rotary element for discharging a fluid upon said vanes to cause said rotary element to rotate.

2. In a flying machine a hollow disk-like member, having air intake and outlet openings, vanes on the circumferential wall of said member, a rotary element therein having a pair of arms projecting close to said vanes, said arms being of a width substantially equal to the distance between the radial walls of said member, and means carried by said rotary element for discharging a fluid upon said vanes to cause said rotary element to rotate, including pipes extending through said arms and having their outer ends adjacent said vanes. 100

3. In a flying machine, a rotary element adapted to produce a downward flow of air, a fixed element, vanes on said fixed element, and means carried by said rotary element for discharging a fluid upon said vanes to cause said rotary element to rotate, said means comprising radial arms on said rotary element, and pipes extending through said arms and having their outer ends adjacent said vanes, and annular explosion chambers on said rotary element from which said pipes lead. 110

4. In a flying machine, a hollow disk-like member having openings in the top and bottom walls thereof adjacent the sides thereof, valves controlling said openings, means for causing a flow of air downward into said member, and a gravity operated control 120 means for said valves.

5. In a flying machine, a hollow disk-like member having openings in the top and bottom walls thereof adjacent the sides thereof, valves controlling said openings, means for 130

- causing a flow of air downward into said member, and a gravity operated control means for said valves, adapted to cause the valves on top and bottom sides to operate inversely in unison.
6. In a flying machine, a hollow disk-like member having openings in the top and bottom walls thereof adjacent the sides thereof, valve controlling said openings, means for causing a flow of air downward into said member, and a gravity operated control means for said valves, adapted to cause the valves on top and bottom sides to operate inversely in unison, said control means comprising levers connected to said valve, a weighted member, and cords leading from said weighted member to said levers.
7. In a flying machine a hollow disk-like member, having air intake and outlet openings, vanes on the circumferential wall of said member, a rotary element therein having a pair of arms projecting close to said vanes, said arms being of a width substantially equal to the distance between the radial walls of said member, and means carried by said rotary element for discharging a fluid upon said vanes to cause said rotary element to rotate, and valves controlling the said openings in the top of the said disk-like member.
8. In a flying machine, a rotary element adapted to produce a downward flow of air, a fixed element, vanes on said fixed element, and means carried by said rotary element for discharging a fluid upon said vanes to cause said rotary element to rotate, a well leading downward to the centre of said rotary element, and a valve for closing said well, said valve comprising a pair of flaps, a pair of links connected at one end to said flaps, a longitudinally movable screw to which the opposite ends of said links are connected, and a nut for moving said screw.
9. In a flying machine, a rotary element, a hollow disk-like member in which said element is mounted, a series of air compressors radiating from the centre of said rotary element and adapted to be operated by rotation thereof, a pair of annular explosion chambers on said rotary element, vanes on said disk-like member, conduits leading from said explosion chambers to points adjacent said vanes, and means for delivering the air from said compressors alternately to the respective explosion chambers.
10. In a flying machine, a rotary element, a hollow disk-like member in which said element is mounted, a series of air compressors radiating from the centre of said rotary element and adapted to be operated by rotation thereof, a pair of annular explosion chambers on said rotary element, vanes on said disk-like member, conduits leading from said explosion chambers to points adjacent said vanes, and means for delivering the air from said compressors alternately to the respective explosion chambers, including a longitudinally movable sleeve valve, a rod connected thereto, and right and left hand spiral elements with which said rod is adapted to be alternately engaged.
11. In a flying machine, a valve operating means comprising a pair of hinged arms, ropes connected thereto, fingers projecting therefrom, and other ropes connected to said fingers.
12. In a flying machine, a rotary element, a hollow disk-like member in which said element is mounted, a series of tandem-cylinder air compressors radiating from the centre of said rotary element and adapted to be operated by rotation thereof, a pair of annular explosion chambers on said rotary element, vanes on said disk-like member, conduits leading from said explosion chambers to points adjacent said vanes, and means for delivering the air from said compressors alternately to the respective explosion chambers.
13. In a flying machine, a hollow disk-like member having openings in the top and bottom walls thereof adjacent the sides thereof, valves controlling said openings, a well leading downward into said disk-like member, an exhaust conduit leading rearward from said disk-like member, and valves in said well and exhaust conduit.
14. In a flying machine a hollow disk-like member having openings in the top and bottom walls thereof adjacent the sides thereof, valves controlling said openings, a well leading downward into said disk-like member, an exhaust conduit leading rearward from said disk-like member, and valves in said well and exhaust conduit, and means for operating said valves inversely in unison.

In testimony whereof I have affixed my signature.

WILLIAM BROWN
